United States Patent

Des. 237,315
Patented Oct. 21, 1975

237,315

INCUBATOR TRAY

Edward Nowakowski, Chicago, and Harry James Pappas,
Hinsdale, Ill., assignors to Miles Laboratories, Inc.,
Elkhart, Ind.

Filed Mar. 4, 1974, Ser. No. 447,488

Term of patent 14 years

Int. Cl. D24—99

U.S. Cl. D83—1 U

FIG. 2

FIG. 3

FIG. 1 is an isometric view of an incubator tray showing our new design.

FIG. 2 is a side elevation view of the tray taken along line 2—2 of FIG. 1.

FIG. 3 is a top plan view of the tray of FIG. 1.

We claim:

The ornamental design for an incubator tray, substantially as shown and described.
